UNITED STATES PATENT OFFICE.

EUGENE R. CARICHOFF, OF SCHENECTADY, NEW YORK, ASSIGNOR TO GENERAL ELECTRIC COMPANY, A CORPORATION OF NEW YORK.

RELAY FOR TWO-WIRE NOTCHING SYSTEMS.

1,077,972.

Specification of Letters Patent.

Patented Nov. 11, 1913.

Application filed August 9, 1911. Serial No. 643,086.

To all whom it may concern:

Be it known that I, EUGENE R. CARICHOFF, a citizen of the United States, residing at Schenectady, county of Schenectady, State 5 of New York, have invented certain new and useful Improvements in Relays for Two-Wire Notching Systems, of which the following is a specification.

This invention relates to the control of 10 electrically operated switches and particularly to the control of a plurality of such switches or contactors intended for operation in succession: such, for example, as are customarily used in controlling electric rail- 15 way motors.

The present invention has especial reference to the system of control disclosed in my Patent 982,032, January 17, 1911. In this patent, and also in my pending application 20 filed August 12, 1910, Serial No. 576,927, I have shown a relay in which there is a series coil or coils which hold the relay open until the current value decreases to a certain point. In said application the series coil 25 is shown as provided with an adjustable core, in order to regulate its influence upon the cores of the relay coils. The present case relates to improvements in the structure of said relay in order to obtain with more 30 accuracy a varying current limit to suit varying conditions of service. This coil can be set to hold at a high current so that the car will mount grades, and yet this high current will not occur on levels. The construction is such that as the current in the 35 series coil increases, the time of descent of the relay plunger increases, so that the intervals between the operation of the contactors will increase correspondingly, and the motor 40 will speed up more slowly. The plunger of the relay coil has a dashpot which would ordinarily permit it to descend in the same time after each deenergizing of the relay coil. In order to retard this descent in ac- 45 cordanee with the current in the series coil, I cause the magnetic field of the series coil to affect the plunger, and resist to a greater or less extent the downward pull of gravity tending to close the relay contacts. Adjust- 50 ability is obtained by movable cores in the series coil which can be adjusted to give a greater or less air gap in the magnetic circuit. There is also an adjustable stop in the upper end of the relay spool which varies

the vertical play of the movable core or 55 plunger of said relay. The spool has a fixed tubular core or bushing which co-operates with the movable core to determine the point at which the plunger will hang suspended. When the car is running on a 60 level, the plunger will drop quicker than when the car is mounting a grade, because the load is less and the motor will more quickly generate sufficient counterelectromotive force to cut down the current and counteract the retarding effect of the series coil. 65

In the accompanying drawings, Figure 1 is a diagram of a two wire notching system of motor control; Fig. 2 is a front elevation, partly in section, of the relay; and Fig. 3 is 70 an end elevation of the same.

There is nothing novel in the system shown in Fig. 1, and it has been fully disclosed and described in my patent above referred to. In brief, it may be said here 75 that when the master controller C is moved to the position *x*, the relay L will be energized, its circuit being traceable from the finger *c* to wire 1, solenoid L, interlock 2 on the core of the relay R, wires 3 4, interlock 5, on the movable core of the contactor 6, coil 7 of said contactor and wire 8 to ground at G. The bridging contact of the interlock 5 is loose on the stem of the contactor core, and is not lifted by the collar 9 thereon until after the interlock 10 on said stem has closed a holding circuit 11 established through the finger *b* of the controller. The lifting of the contactor stem also causes the interlock 12 to close a circuit 80 from the wire 1 by way of the solenoid R, interlock 13 on the plunger of the relay L, wires 14, 15, 16, interlock 17 on the stem 85 of the contactor 18, solenoid 19 of said contactor and wire 8 to ground. This circuit, 90 however, has been opened at the interlock 13 when the relay L was energized and its plunger lifted, and the said circuit of the relay R will not be established until the plunger of relay L descends. The closing 100 of the contactor 6 sends current to the motor M through the resistors R', R², R³. The second contactor 18 will cut out the first resistor, but this cannot take place until the plunger of relay L descends and closes the 105 interlock 13. Its descent is retarded both mechanically and electrically; the latter effect being produced by the series coil 20

in the power circuit of the motor M from the button *a* of the master controller C, and acting to give a variable time limit to the descent of the plunger.

Referring now to Figs. 2 and 3, the relay is seen to have a frame composed of two parallel bars 21 22 of iron or other magnetic material spaced apart by posts 23 of brass or other non-magnetic material. Between said bars is located the series coil 20 composed of a few turns of heavy conductor wound on a tube 24 of insulating material clamped between the bars. Cores 25 25' are tapped through said bars and project into the tube 24, affording means for adjusting the length of the air gap 26 between their ends. The relay coils 27 28 are wound on spools of insulating material which are clamped between the ends of the bars 21 22, one on each side of the series coil. Each spool has a tubular bushing, the lower portion 29 being of brass or other non-magnetic material and the upper portion 30 being of steel or other magnetic material. The bushing 30 is extended upwardly through a hole in the bar 21 and is tapped to receive a brass screw plug 31 which serves as an adjustable stop to limit the upward movement of the movable core or plunger 32 which has a sliding fit in the bushing of the spool, and extends down through a hole in the lower bar 22. The vertical play of the plunger when the adjusting screw is run up to the top of the spool is preferably about three-quarters of an inch. The plunger carries a contact disk 33 fitting loosely on said plunger, and held yieldingly on a shoulder 34 by a spring 35. This disk makes contact with the contacts 36 supported on brackets 37. On the lower end of the plunger is secured the movable member of an air dashpot 38, which is adjusted to let the plunger drop through its entire range of movement in about eight-tenths of a second when there is no current flowing in the coils. At 39 is shown the terminal for connecting the wire 1 of Fig. 1, and at 40 41 are the terminals for the wires 3 and 14.

The principle of operation of the two wire notching system is, that so long as the operator keeps the master controller fully closed the contactors will close automatically in succession until all the resistors have been cut out and the motor is connected directly to the line. Each contactor as it closes also closes a break in the circuit of the next contactor, and this circuit is completed when the plunger of the relay in circuit with the former contactor falls by reason of the open circuiting of said relay by the closing of said former contactor. Thus the relays open and close alternately, and all the contactors after the first one are dependent upon the alternate closing of the relays to enable them to operate. Hence by varying the time it takes

the relay plungers to drop, the rate of acceleration of the motor can be controlled. The relay construction above described enables this control to be very accurately exerted.

Assume that when the master controller C is moved to position *a* the current permitted to flow through the resistors R', R², R³ to the motor is 250 amperes. This current, passing through the series coil 20, will set up a magnetic flux in the cores 25 25', the bars 21 22, the bushing 30 and the plunger 32, which will be sufficient to just balance the weight of said plunger when it has been lifted by the coil 27. Upon the deenergizing of the coil 27 the plunger will start to drop and will descend easily until its top reaches the lower end of the bushing 30. Here the flux set up by the series coil will oppose the lengthening of its path by the separation of the plunger from the bushing, and therefore the plunger will be sustained in this position indefinitely by the flux generated by this current of say, 250 amperes. So long, therefore, as the current flowing to the motor remains at this value the interlock 13 will not close, and no more resistors will be cut out. But when the motor speeds up and its counterelectromotive force cuts down the current, the sustaining power of the series coil becomes weaker, and the plunger begins to descend. Its descent is opposed by the dash-pot 38, and its speed will depend upon the unbalanced portion of its weight, which depends upon the amount of decrease in the current in the series coil. At 225 amperes it may require 2.5 seconds for the plunger to drop completely; at 200 amperes the descent will occur in 2.1 seconds; at 150 amperes in 1.7 seconds, and so on. The more rapidly the current is cut down the faster the plunger will drop. If, therefore, the car starts on a level road, where it can accelerate rapidly, the contactors will close quickly and cut out the successive resistors in a short time. But when the car is on an up grade the rate at which the current will be cut down by the counterelectromotive force of the motor will be slower, and consequently the descent of the plungers will be slower, owing to the greater retarding effect of the series coil flux. This prevents the resistors from being cut out while the current remains at a high value, cuts them out very slowly if the current drops only a little below that value, and more rapidly if the drop is greater.

The minimum current at which the series coil will hold the plunger from dropping can be varied by screwing the cores 25 25' in or out to vary the length of the air gap 26 in the magnetic circuit of said coil; the holding current being higher when the length of the gap increases and vice versa.

The adjusting screw 31 permits of varying the stroke of the dashpot and thereby vary-

ing to some extent the time of descent of the plunger.

In accordance with the provisions of the patent statutes I have described the principle of operation of my invention, together with the apparatus which I now consider to represent the best embodiment thereof; but I desire to have it understood that the apparatus shown is only illustrative and that the invention can be carried out by other means.

What I claim as new and desire to secure by Letters Patent of the United States, is,—

1. A system of motor control comprising a relay having magnetic plungers controlling circuits, coils for lifting said plungers, dash-pots for retarding their descent, a magnetic structure including said plungers, and a series coil with cores connected with said structure for setting up a flux in said structure.

2. A system of motor control comprising a relay having magnetic plungers controlling circuits, coils for lifting said plungers, dash-pots for retarding their descent, a magnetic structure including said plungers and in which their descent increases an air gap, and a series coil for setting up a flux in said structure.

3. A system of motor control comprising a relay having two bars of magnetic material, relay coils between said bars, bushings for the spools of said coils, composed in part of magnetic material, magnetic circuit controlling plungers working in said bushings, means for retarding the descent of said

plungers, and a series coil between said bars with cores connected with said bars.

4. A relay comprising two bars of magnetic material, cores tapped into said bars, a series coil concentric with said cores, relay coils between said bars, bushings for said coils whose upper portions only are magnetic, and circuit controlling plungers of magnetic material entering the lower part of said relay coils.

5. A relay comprising two bars of magnetic material, cores tapped into said bars, a series coil concentric with said cores, relay coils between said bars, bushings for said coils whose upper portions only are magnetic, circuit controlling plungers of magnetic material entering the lower part of said relay coils, and adjustable stops entering the upper part of said relay coils.

6. A relay comprising two bars of magnetic material, cores tapped into said bars, a series coil concentric with said cores, relay coils between said bars, bushings for said coils whose upper portions only are magnetic, circuit controlling plungers of magnetic material entering the lower part of said relay coils, and dash-pots connected to said plungers for retarding the descent thereof.

In witness whereof, I have hereunto set my hand this 7th day of August, 1911.

EUGENE R. CARICHOFF.
